(57) **CLAIM**

An ornamental design for the handle for a lifting device as shown and described.

DESCRIPTION

FIG. 1 is a top, front and left perspective view of a handle for a lifting device, showing our new design;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken-lines in the drawings depict portions of the handle for a lifting device that form no part of the claimed design.
